UNITED STATES PATENT OFFICE.

HARRY W. HILL, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

DESIGN FOR A LENS-BLANK.

59,842.

Specification for Design.

Patented Nov. 29, 1921.

Application filed April 21, 1921. Serial No. 463,406. Term of patent 14 years.

To all whom it may concern:

Be it known that I, HARRY W. HILL, a citizen of the United States, residing at Southbridge, in the county of Worcester and State of Massachusetts, have invented a new and original ornamental Design for Lens-Blanks, of which the following is a specification, reference being made to the accompanying drawings, forming a part thereof.

The drawing illustrates my new ornamental design for a lens blank.

I claim:

The ornamental design for a lens blank substantially as illustrated.

In testimony whereof, I affix my signature in the presence of two witnesses.

HARRY W. HILL.

Witnesses:

SUSAN CASAZZA,
ALICE G. HASKELL.
